UNITED STATES PATENT OFFICE.

JACOB CASHMER, OF DENVER, COLORADO, ASSIGNOR, BY MESNE ASSIGNMENTS, TO
UNIVERSAL SAFETY WASHOUT PLUG COMPANY, A CORPORATION OF COLORADO.

WASHOUT PLUG FOR BOILERS.

Application filed March 9, 1921. Serial No. 450,957.

To all whom it may concern:

Be it known that I, JACOB CASHMER, a citizen of the United States, residing at Denver, in the county of Denver and State of Colorado, have invented certain new and useful Improvements in Washout Plugs for Boilers, of which the following is a specification.

This invention relates to washout plugs for boilers and its primary object is to provide a plug which has an opening to permit of the passage of water without its removal from the opening in the wall of the boiler or other vessel in which it is fastened, and a readily detachable cover of simple construction which normally covers the same.

Another object of the invention is to provide a fluid-tight joint between the cover and the body portion of the plug by means of a gasket or other packing seated in a continuous groove in one of the parts, and a ridge adapted to forcibly engage the packing on the other part, and still other objects reside in details of construction and arrangements of parts which will be fully disclosed in the following description with reference to the accompanying drawings which show an embodiment of the invention.

In the drawings in the various views of which like parts are similarly designated,

Figure 1 is an axial section through my improved plug in its operative position in an opening of the wall of a boiler or other vessel;

Figure 2, an elevation of the plug showing the cover thereof in position for its removal;

Figure 3, a section on the line 3—3, Figure 2;

Figure 4, an end view of the plug shown in Figure 2, looking in the direction of the arrow A, after the nut by which the cover is secured, has been removed;

Figure 5, a sectional elevation of the plug showing a modification in its construction, and

Figure 6, an elevation of a gasket used in the production of the fluid-tight joint between the body portion of the plug and the removable cover.

Referring to the drawings, the reference character 2 designates the wall of a boiler or other vessel having an opening which is tapped for a correspondingly screw-threaded plug.

The plug of the present invention consists of an externally threaded body member 3 which has an oblong passage 4 terminating at a distance from its front edge, and a cylindrical space 5 formed forward of said passage to receive a correspondingly formed part of an abutment member hereinafter to be described.

The body 3 has at its opposite end around the oblong passage, a correspondingly formed ridge 6 which forms part of the fluid-tight joint between the body and the cover member of the plug.

This cover member consists of an oblong plate 7 having a marginal channel 8 around a central core 9 which is grooved to receive the eye-shaped head 10 of a retaining bolt 12 which is movably connected to the cover by a pivot pin 13.

The channel which is formed and proportioned to freely admit the ridge at the end of the body when the cover is in place, is slightly dove-tailed in cross-section to retain a gasket 13 or other packing placed in its bottom portion.

The channel has furthermore and for the same purpose a shallow recess 14 in one of its sides adapted to receive a corresponding projection 15 on the gasket 13 shown in detail in Figure 6 of the drawings.

The packing may be made of any suitable material and placed in the channel in any convenient manner in either a dry or molten condition, and it is permanently held in place by the above described means.

The cover member is sufficiently small in width to permit of its moving freely through the passage of the body member when it is folded upon the bolt as illustrated in Figures 2 and 4 of the drawings.

When the cover member is in its closing position with relation to the body member of the device, it is clamped in place by the engagement of a nut 16 screwed upon the retaining screw, with an abutment member 17 hereinbefore referred to.

This abutment member consists in the form shown in Figures 1, 2 and 4, of a lid which engages the front edge of the body member and which is movably connected therewith by a hinge joint 18.

The lid which fits loosely within the circular space 5 at the front end of the body member has a flange 19 in engagement with the edge of the same, and it is provided with

a radial slot 20 to admit the retaining bolt 12.

When the cover member is in place on the body member as shown in Figure 1, 5 the nut 16 is screwed upon the retaining bolt passing through the slot of the abutment member, into engagement with the outer surface of the same.

The ridge 6 on the body member forcibly 10 brought in engagement with the packing in the channel 8 of the cover member, produces a fluid-tight joint and when it is desired to open the plug for the admission or discharge of a liquid or other fluid to or 15 from the vessel with which it is connected, the cover member is readily removed by first unscrewing the nut 16, then moving the abutment member about its hinge to the position shown in Figure 2, and finally 20 drawing the cover member through the passage of the plug after it is folded upon the retaining bolt.

It will be apparent that this means of uncovering the opening of the boiler is advantageous over the old method of removing the entire plug inasmuch as it requires less effort and time on the part of the attendant, does not injure or wear the screw thread by 25 which the plug is fastened in the opening 30 and prevents the blow-outs often occurring in the use of ordinary plugs.

The body member has in its shoulder 21 at the end of its oblong passage a pair of recesses 22 to receive the ends of a spanner wrench for the purpose of tightening or 35 removing the plug 3, and a cotter pin 23 applied at the end of the retaining bolt prevents the nut from being entirely removed therefrom, thereby maintaining the parts 40 in their relative position, for instant readjustment whenever it is desired to replace the cover member.

In the modified construction shown in Figure 5 the abutment member 24 is formed 45 integral with the nut 25, and the flange which in the first-described construction engages the edge of the body member at the front end thereof is eliminated.

When the nut 25 is screwed home, the 50 plate 24 which fits inside the circular space at the front end of the body member, is brought in engagement with the shoulder 21 at the end of the oblong passage of the same and thus performs the function of the 55 hinged lid of the other form.

The last-described construction is particularly adapted for use in places where the space outside the boiler is too limited to 60 permit of removal of the long retaining screw of the form shown in Figures 1 and 2.

Having thus described my invention what I claim and desire to secure by Letters-Patent is:

1. A device of the character described 65 comprising a hollow body member adapted

to be secured in an opening of a boiler wall, a cover member movable through said body member and adapted to close the same by engagement with an end thereof, a retaining screw pivoted on the cover member, and a 70 nut on the screw acting upon the opposite end of the body member to hold the cover member in its closing position.

2. A device of the character described comprising a hollow body member adapted 75 to be secured in an opening of a boiler wall, a cover member movable through said body member and adapted to close the same by engagement with an end thereof, a retaining screw pivoted on the cover member, an 80 abutment member engaging the other end of the body member, and a nut on the screw cooperating with the abutment-member to hold the cover member in its closing position. 85

3. A device of the character described comprising a hollow body member adapted to be secured in an opening of a boiler wall, a cover-member movable through said body member and adapted to close the same by 90 engagement with an end thereof, a retaining screw pivoted on the cover member, an abutment member engaging the other end of the body member, and a nut on the screw 95 engaging with the abutment-member to hold the cover member in its closing position.

4. A device of the character described comprising a hollow body member adapted to be secured in an opening of a boiler wall, 100 a cover member movable through said body member and adapted to close the same by engagement with an end thereof, a retaining screw pivoted on the cover member, an abutment member hinged on the body member and having a slot to admit the bolt, and a nut 105 on the bolt engaging the abutment-member.

5. A blow-out plug comprising an externally screw-threaded hollow body member, a cover member movable through said body member and adapted to close the same by 110 engagement with an end thereof, a bolt pivoted on the cover member, and a nut on the bolt bearing upon the opposite end of the body member to hold the cover member 115 in its closing position.

6. In combination, a hollow body adapted to be secured in an opening of a boiler wall and having at an end a ridge circumscribing its opening, a cover adapted to close said body and having a channel formed to admit said ridge, a packing in the bottom of the channel, and holding-means acting upon the cover to forcibly bring the ridge in engagement with the packing. 120

7. In combination, a hollow body adapted to be secured in an opening of a boiler wall and having at an end a ridge circumscribing its opening, a cover adapted to close said body and having a channel of dovetail section adapted to admit said ridge, a 125 130

packing occupying the bottom of the channel, and holding-means acting upon the cover to forcibly bring the ridge in engagement with the packing.

5 8. In combination, a hollow body adapted to be secured in an opening of a boiler wall and having at an end a ridge circumscribing its opening, a cover adapted to close said body and having a channel formed to 10 admit said ridge, the channel having in one of its walls a laterally extending narrow recess a gasket occupying the bottom of the channel and having a projection fitted in the recess, and holding means acting 15 upon the cover to forcibly bring the ridge in engagement with the packing.

9. A device of the character described comprising a body member adapted to be secured in an opening of a boiler wall, having 20 an oblong passage and a circular space at an end thereof, a cover member movable through said passage and adapted to close the same by engagement with an end of the body member, a bolt pivoted on the 25 cover member, an abutment member removably disposed in said space, and a nut on the bolt cooperating with the abutment member to hold the cover in its closing position.

30 10. A device of the character described comprising a body member adapted to be secured in an opening of a boiler wall, having an oblong passage and a circular space at an end thereof, a cover member movable 35 through said passage and adapted to close the same by engagement with an end of the body member, a bolt pivoted on the cover member, an abutment member remov-

ably disposed in said space, and having a flange engaging the end of the body member, 40 and a nut on the bolt cooperating with the abutment member to hold the cover in its closing position.

11. A device of the character described, 45 comprising a hollow body member adapted to be secured in an opening of a boiler wall, said member having a ridge circumscribing its opening at an end thereof, an oblong channeled cover member movable through the body member and adapted to close the 50 same by engagement with said ridge, a packing in the channel of the member with which the ridge engages, a bolt pivoted on the cover-member, an abutment member engaging the opposite end of the body member, 55 and a nut on the bolt cooperating with the abutment member to hold the cover member in its closing position.

12. A device of the character described, 60 comprising a hollow body member adapted to be secured in an opening of a boiler wall, said member having a ridge circumscribing its opening at an end thereof, an oblong channeled cover member movable through the body member and adapted to close the 65 same by engagement with said ridge, a packing in the channel of the member with which the ridge engages, a bolt pivoted on the cover-member, and a nut on the bolt 70 acting upon the opposite end of the body member to hold the cover member in its closing position.

In testimony whereof I have affixed my signature.

JACOB CASHMER.
